CLAIM

The ornamental design for a tire for two-wheeled vehicles, as shown and described.

DESCRIPTION

FIG. 1 is a perspective view of a tire for two-wheeled vehicles showing our new design it being understood that the tread design is repeated uniformly throughout the circumference of the tire as shown schematically in solid lines and the opposite side is the same as that shown;

FIG. 2 is a front elevation view thereof; and

FIG. 3 is a side elevation view thereof on a reduced scale.

FIG 1

FIG 2

FIG. 3
